UNITED STATES PATENT OFFICE.

GEORGE WILKINSON, OF PROVIDENCE, RHODE ISLAND, ASSIGNOR TO THE GORHAM MANUFACTURING COMPANY, OF SAME PLACE.

DESIGN FOR A SPOON.

SPECIFICATION forming part of Design No. 21,804, dated June 7, 1892.

Application filed May 3, 1892. Serial No. 431,725. Term of patent 7 years.

To all whom it may concern:

Be it known that I, GEORGE WILKINSON, a citizen of the United States, residing at Providence, in the county of Providence and State of Rhode Island, have invented and produced a new and original Design for Spoons, of which the following is a specification, reference being had to the accompanying drawing, forming part thereof.

10 The drawing represents a view of a spoon and the handle thereof, illustrating my new design.

The leading features of my new design consists in the base of the handle joining the upper portion of the bowl, a contracted neck extending from said base in symmetrical curving outlines, gradually increasing the width of the handle and curving inward at the top thereof to meet the curved outline of a central ornament. Surface ornamentation in which a foliated ornament having its spreading base partially contained within the bowl-outline extends upward on a central convex portion of the handle and gradually tapering, a border-line extending practically parallel with the outline of the handle, broken at intervals by small inwardly-projecting scrolled ends and outwardly-projecting and slight foliations, slight concavities inside of this border-line at the upper end thereof; an inner border formed of a combination of slightly-foliated scrolls rising from a shell-like base, beneath which are represented spreading scrolls, a portrait-bust within said inner border, and a view of a cloister depicted on the surface of the handle below the portrait, and figures in the foreground of the view.

35 Number 2 in the drawing indicates the bowl of the spoon, and 3 is the handle extending up-

ward from the bowl. The outline of the handle spreads very slightly to 4, where it is abruptly contracted for a short distance at each side and curving slightly inward and then outward forms the neck and first enlargement 5, above which the outline again curves outward, forming the enlargement 6, the upper line of which is curved inward to meet the ends of the short curved line 7. The handle-border is formed by the lines 8 8, extending practically parallel with the outline and at a short distance therefrom, being broken at intervals by the inwardly-turned scrolled ends 9 9 and the outwardly-extending foliations 10 10, and ending in scrolled ends 11 11 at the upper end of the handle, these ends being connected by a short curved line. The foliated ornament 12 has a spreading base on the upper surface of the bowl and extends upward along the greater portion of the convex rib 13. On the enlargement 6 is represented an inner border or frame 14, formed of a combination of scrolled and slightly-foliated ornaments rising from the shell-like ornament 15, below which is a branching scroll 16. Within this frame 14 is represented a portrait, and outside the upper portions thereof are slight concavities 17. The main portion of the handle below the scroll 16 is ornamented with a view of a cloister, in which three seated figures are shown in the foreground.

What I claim is—

The design for a spoon, as herein shown and described.

GEORGE WILKINSON.
